[57] CLAIM

The ornamental design for an eyeglass display fixture, as shown and described.

DESCRIPTION

FIG. 1 is a top, front, and left side perspective view of an eyeglass display fixture showing our new design, the broken line disclosure of an additional fixture, eyeglasses, and partial display panel are for illustrative purposes only and form no part of the claimed design;

FIG. 2 is an enlarged front elevational view thereof;

FIG. 3 is an enlarged top plan view thereof;

FIG. 4 is an enlarged right side elevational view thereof;

FIG. 5 is an enlarged left side elevational view thereof;

FIG. 6 is an enlarged rear elevational view thereof;

FIG. 7 is an enlarged bottom plan view thereof;

FIG. 8 is a top, front, and left side perspective view thereof, the broken line disclosure of an additional fixture and partial display panel are for illustrative purposes only and form no part of the claimed design; and,

FIG. 9 is top, rear, and right side perspective view thereof, the broken line disclosure of an additional fixture and partial display panel are for illustrative purposes only and form no part of the claimed design.
